(57) **CLAIM**

The ornamental design for the housing for a portable memory device, as shown and described.

DESCRIPTION

FIG. 1 is a rear perspective view of a housing for a portable memory device showing my new design with the connector in the retracted position;

FIG. 2 is a top view thereof;

FIG. 3 is a right side view thereof;

FIG. 4 is a bottom view thereof;

FIG. 5 is a left side view thereof;

FIG. 6 is a rear view thereof;

FIG. 7 is a front view thereof;

FIG. 8 is a rear perspective view thereof, showing the design with the connector in the extended position;

FIG. 9 is a top view thereof, showing the design with the connector in the extended position;

FIG. 10 is a right side view thereof, showing the design with the connector in the extended position;

FIG. 11 is a bottom view thereof, showing the design with the connector in the extended position;

FIG. 12 is a left side view thereof, showing the design with the connector in the extended position;

FIG. 13 is a rear view thereof, showing the design with the connector in the extended position; and,

FIG. 14 is a front view thereof, showing the design with the connector in the extended position.

The broken lines showing the connector feature are for the purpose of illustrating environmental structure and form no part of the claimed design.
